Primary Examiner — Michelle E. Wilson*Assistant Examiner* — Clese Moore, Jr.(74) *Attorney, Agent, or Firm* — Advantage IP Law Firm(57) **CLAIM**

The ornamental design for a vehicle running board, as shown and described.

DESCRIPTION

FIG. 1 is an upper perspective view of a vehicle running board shown attached to an exemplary vehicle portion illustrating our new design;

FIG. 2 is a right outboard view thereof;

FIG. 3 is a left inboard view thereof;

FIG. 4 is a top view thereof;

FIG. 5 is a bottom view thereof;

FIG. 6 is a front view thereof; and,

FIG. 7 is a rear view thereof.

All dashed lines are for environmental purposes only and form no part of the claimed design.
